UNITED STATES PATENT OFFICE.

ISAAC T. DYER, OF CHICAGO, ILLINOIS, ASSIGNOR TO HIMSELF AND PETER FISH, OF SAME PLACE.

APPARATUS FOR HEATING CARS.

SPECIFICATION forming part of Letters Patent No. 409,278, dated August 20, 1889.

Application filed November 25, 1887. Serial No. 256,040. (No model.)

To all whom it may concern:

Be it known that I, ISAAC T. DYER, a citizen of the United States, and a resident of Chicago, county of Cook, and State of Illinois, have invented new and useful Improvements in Apparatus for Heating Cars, of which the following is a specification, reference being had to the accompanying drawings, illustrating the invention, in which—

10 Figure 1 is a longitudinal elevation of a locomotive-boiler and fire-box, part in elevation and part in section, an air-pump in section, and an elevation of the other portion of the apparatus by which a car is heated; Fig. 15 2, a plan or top view of the air-pipes in the fire-box removed; Fig. 3, a sectional elevation of the injector and its connections.

In brief, the invention consists in air-pipes placed in the fire-box and an air-pump to 20 force hot air by means of suitable pipes into the cars when the same are being moved by a locomotive, and an injector to put hot air into the cars when the locomotive and cars are not moving. When the pump stops, the 25 injector is automatically put in motion.

3 represents the boiler, and 4 the fire-box, of an ordinary locomotive.

J J represent pipes which are placed transversely in the fire-box and connected with 30 pipes I I, &c., which run longitudinally with the fire-box and at right angles to the pipes J, so that air may circulate freely through all of them. In these pipes the air coming from the pump G is heated, and from them the 35 air is discharged by means of a pipe X, which communicates with the outer pipe J, and which may have coupled to it a pipe leading to a car to be heated, in the ordinary manner of connecting hot-air pipes. By 40 means of a vertical pipe K and a horizontal pipe H air is conducted from a cylinder A to the inner pipe J, and by means of a suitable air-chamber L, attached to and communicating with cylinder A and a pipe M, attached to the cylinder and to an air-force 45 pump G, and communicating with them, the air taken by the pump G is delivered through the pipe X, and during its passage is heated in the pipes J K L.

50 The pump G is of ordinary construction,

having four valves and two connections with pipe M. The pump is to have given to it the ordinary movement by means of crank P, which is attached to an ordinary yoke S, and the yoke is placed on an ordinary eccentric 55 T, which is attached to the axle N of a locomotive-truck. The air is forced by the pump G into a chamber L, to equalize the pressure, and from the said chamber it enters the cylinder A, forcing the piston 5 up past the pipe 60 H. By this movement the piston-rod E', having a loose connection with a lever D, elevates the free end of said lever and closes a cock C in a steam-pipe F, to which it is attached in the ordinary manner so long as air 65 coming from the pump keeps the piston 5 elevated, as stated. The injector is idle, but as soon as the pump stops work the piston 5 will fall down to the position shown, the cock C in steam-pipe F will be opened and steam from 70 the dome 6 will pass through said pipe, enter the narrow passage B of pipe H, and pass on in the direction indicated by dart 8, Fig. 3, and air taken in at the top 7 of cylinder, by means of an opening E, will follow the steam 75 into pipes K I J in the ordinary manner of an injector's operation.

By the foregoing it will be seen that air will be put through the pipes K I J so long as there is steam in the boiler, notwithstanding the pump G is idle.

I claim as new and desire to secure by Letters Patent of the United States—

The combination of the pump G, air-chamber L, and pipe M, connecting said pump and 85 air-chamber, cylinder A, open at its top and communicating with chamber L, pipe H, communicating with cylinder A midway thereof, piston 5, operating in cylinder A and provided with an operating-rod E', injector F, 90 communicating with pipe H, the cock C, located in said injector F, lever D, connecting cock C with the piston 5 by means of rod E', and pipes K I J, communicating with pipe H, substantially as shown and described.

ISAAC T. DYER.
